SCRAPING APPARATUS

Joseph H. Kerber, Milwaukee, Wis., assignor to
 Hi-Way Service Corporation, Milwaukee, Wis.,
 a corporation of Wisconsin

Application June 6, 1938, Serial No. 212,021

3 Claims. (Cl. 37—144)

The invention relates to material-handling apparatus and more particularly to those forms of apparatus employing scraper blades such as used as bulldozers, backfillers, and snowplows.

5 The main object of the invention is to provide a construction in which the scraper blade may be given a vertical angular adjustment through operating connections controlled by the operator of the vehicle on which the scraper is mounted. 10 Heretofore, any vertical angular adjustments have had to be made while the vehicle was standing still, while with the present invention the cutting angle may be changed without getting out of the machine and at any time which greatly facilitates the scraping of a road to any desired inclination.

15 A further object of the invention is to provide a connection for the scraper blade at spaced points which will shorten the over all length of the machine.

20 A further object of the invention is to provide an arrangement in which the scraper is angularly adjustable relative to the direction of travel of the vehicle and may also be positioned 25 at right angles to said direction of travel.

The invention further consists in the several features hereinafter set forth and more particularly defined by claims at the conclusion hereof.

In the drawings:

30 Fig. 1 is a side elevation view of a tractor equipped with a scraping apparatus embodying the invention;

35 Fig. 2 is a plan view of the apparatus, parts being broken away and parts shown in section;

Fig. 3 is a detailed vertical sectional view on the line 3—3 of Fig. 2;

Fig. 4 is a detailed vertical sectional view through the line 4—4 of Fig. 2;

Fig. 5 is a vertical sectional view taken on the 40 line 5—5 of Fig. 1;

Fig. 6 is a diagrammatic view of the apparatus with the scraper blade in one angular position;

Fig. 7 is a diagrammatic view of the apparatus with the scraper blade in a straight position;

45 Figs. 8 to 12 are views of the scraper in various positions of vertical adjustment;

Fig. 13 is a detailed sectional view on the line 13—13 of Fig. 2.

In the drawings, the numeral 15 designates 50 a tractor of known construction of the full crawler type having endless propelling treads 16 running over sprockets 17 and 17', here shown conventionally at the front and rear portions of the tractor and over the usual truck or tread 55 rollers (not shown) mounted in the truck or

tread frames 18. As is usual, the rear sprockets 17 are driven from the engine housed in the housing 19 through a suitable transmission (not shown) and under the control of the operator or driver of the tractor from his seat 20, these 5 controls not being specifically shown.

The truck frames 18 include frame members to which pivot forming brackets 21 are secured, said brackets having ball shaped pivot ends 22 upon which the side frame members 24 of the 10 implement or blade-supporting frame are pivotally mounted. This supporting frame further includes frame members 25 which are adjustable lengthwise relative to the members 24 and may also include a triangular frame member 26 adapted to be secured to either of the members 24. The scraper blade or other implement member 27 is adapted to be connected to the members 24, 25, and 26 by pin joints such as that shown in Fig. 4 which includes the removable pin 28 adapted to be passed through holes 29 and 30 in the scraper and frame member respectively, the holes 30 being shown in Fig. 4 as having clearance to accommodate for the vertical angular adjustment of the blade. 25

Angled brackets 31 are secured to the truck frame parts 32 by bolts 33, and U-shaped lever members 34 straddle the front ends of the truck frames 18 and are pivotally connected to each set of brackets by pivot bolts 35. 30

The side frame members 24 preferably carry plates 36 which cooperate with similar plates 37 on the brackets 31 to keep the sides of the supporting frame in proper alignment.

Each member 34 is operatively connected by 35 links 38 with its cooperative side frame member 24.

Each of the supporting frames are independently operable through a hydraulically operated means including a hydraulically operated cylinder 39 pivotally connected at its rear end upon the pivot pin 40 secured to the frame of the tractor and having a piston working in said cylinder with its rod 41 operatively connected to the member 34 by the pivot pin 42. Each of the cylinders 39 is adapted to be supplied through pipe connections 39' with fluid from a suitable source of pressure supply and under the action of a suitable control valve. 40

With the above construction, movement of the rod 41 toward the left swings the lever or member 34 upwardly, and this through the links 38 acts to swing the frame members 24 upwardly and thus lift that end of the scraper blade to which the frame member 24 is connected. Thus 45

since each of the ends of the scraper blade are independently adjustable, the vertical angularity of the blade may be adjusted to suit the requirements of the work.

5 In order to adjust the angle the blade makes in a horizontal plane, the frame member 26 may be connected to either of the angled ends 43 of the side frame members 24 by removable pin connections 44, similar to that shown in Fig. 4, 10 one position being shown in Fig. 2 and the other position shown in Fig. 6.

In either position of angular adjustment, the frame members 25 are connected to the members 24 and 27 to act as braces, such connections 15 being shown in Fig. 6 where one of the braces 25 connects with the outer end of the member 24 and the outer end of the blade and the other connects the outer end of the blade with the inner end of the other member 24 by a removable pin 28 passing through openings in the rear end of the member 25 and the openings 20 29 in the member 24.

For the straight connection, the member 26 is omitted and the scraper blade connected directly to the ends of the frame members 24. 25 Under these conditions the blade is further braced by the connection of the frame member 25 with the end of the blade and with the intermediate part of the member 24, as shown in 30 Fig. 7.

With any of the positions of angular adjustment in a horizontal plane, the connections for lifting the ends of the blade may be operated together to lift the blade 27 vertically from its 35 position shown in Fig. 8, or either end may be raised or lowered relatively to the other to assume the different positions shown in Figs. 9 to 12 inclusive. The swivel or ball and socket joints provided between the pin ends 22 and the 40 sockets 44 on the ends of the levers 24 permit of the ready raising and lowering of one end relative to the other.

It is to be noted that the angled ends 43 are 45 provided with three spaced holes 39 for registering with similar spaced holes 29 in the blade 27 as shown in Fig. 2 in one of the angular positions of the blade, the member 26 being pinned to the blade at the opposite side through one set of the holes 29 while the hole 39 at the 50 junction of the portions 43 and 24 takes a pin 48 to secure it to the rear end of the member 26.

I desire it to be understood that this invention is not to be limited to any particular construction or arrangement of parts except in so far as such limitations are included in the claims.

What I claim as my invention is:

1. The combination with a vehicle, of a scraper blade adapted to work at the front of the vehicle, levers pivotally connected at their rear ends to the vehicle and having their front ends extending inwardly at an angle, means for connecting one of said front ends along its length to the scraper blade, a connector for connecting the front end of the other lever to the other end of said blade to provide an angular disposition of said blade relative to its path of travel, 15 and means for independently raising and lowering said levers to adjust the angle of said blade in a vertical plane relative to the surface over which it travels, and brace means for connecting the ends of the blade with said levers. 20

2. The combination with a vehicle, of a scraper blade adapted to work at the front of the vehicle, levers pivotally connected at their rear ends to the vehicle and having their front ends extending inwardly at an angle, means for connecting 25 said front ends to the central part of said blade, braces connecting said levers to the ends of said blade, and means for independently raising and lowering said levers to adjust the angle of said blade in a vertical plane relative to the surface 30 over which it travels.

3. The combination of a vehicle having an operator's seat at the rear portion, of a scraper blade adapted to work at the front of the vehicle, a main frame for said vehicle, traction means 35 for said vehicle including frames, levers on opposite sides of the vehicle pivotally connected at their rear ends to said traction frames and having their front ends operatively connected to said blade, a hoisting frame pivotally mounted on 40 each traction frame and operatively connected with the lever at that side of the vehicle, an hydraulic cylinder connected with each hoisting frame and pivotally connected with the main frame of the vehicle below the operator's seat 45 for independently raising and lowering said hoisting frames to vary the angle of said blade in a vertical plane relative to the surface over which it travels.

JOSEPH H. KERBER. 50
